UNITED STATES PATENT OFFICE.

DAVID G. WHERRY, OF ALEXANDRIA, NEBRASKA.

ROTARY STEAM-ENGINE.

SPECIFICATION forming part of Letters Patent No. 335,001, dated January 26, 1886.

Application filed September 4, 1885. Serial No. 176,167. (No model.)

To all whom it may concern:

Be it known that I, DAVID G. WHERRY, a citizen of the United States of America, residing at Alexandria, in the county of Thayer 5 and State of Nebraska, have invented certain new and useful Improvements in Rotary Steam-Engines; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to certain new and useful improvements in rotary engines; and it consists in the construction and combination of the parts, as will be hereinafter fully set forth, and specifically pointed out in the claims.

20 In the accompanying drawings, which illustrate my invention, Figure 1 is a perspective view of my improvement, showing the exterior of the engine with the supply and exhaust pipes removed therefrom. Fig. 2 is an end 25 view showing the valve-covering plates and center valve-operating mechanism removed. Fig. 3 is an interior view of the wheel and casing. Fig. 4 is a side view showing the valve-covering plates and supply and 30 exhaust pipes attached to the casing. Fig. 5 is a perspective view of the valve-operating plates, and Figs. 6, 7, and 8 are detailed perspective views.

35 In the accompanying drawings, A represents the casing, which is provided on its interior, adjacent to its inwardly-projecting flange a , with a recess or circumferential groove, a' , which groove is bisected by vertically-moving cut-offs B, which operate in a 40 recess in the flange, which recess extends below the plane of the groove a' . A perspective view of one of these cut-offs is shown in Fig. 6 of the accompanying drawings.

45 To the exterior or outer edge of the casing A is secured a plate, C, through which the shaft D passes, to which shaft the rotary piston E is rigidly attached. This piston is provided on both its faces with an eccentric groove, e , into which grooves fit the projecting pins d of 50 the sliding blocks F, which move in vertical grooves A' in the casing. These sliding blocks, which are operated by the rotary piston, are

connected to the cut-offs B by sliding bars D', which are provided with perforations into which fit the cross-bars d' of the cut-offs B and 55 the projecting pins d of the sliding blocks F. The rotary piston is provided with the projecting portion E', which abuts against the inner surface of the flange a , and it is against this projecting portion that the live steam acts 60 to cause the rotation of the piston.

g and g' indicate the entrance-ports of the steam, the exhaust-ports being indicated by h and h' .

65 By the construction thus described, when the piston is rotated and the projecting portion E' thereof approaches the cut-offs, said cut-offs will be depressed, so that the wheel or piston may pass the same, this movement being caused by the sliding blocks, which are reciprocated by the pins thereon moving in the eccentric grooves in the faces of the piston, said movement being imparted to the cut-offs at the proper time.

70 The side casings are each similarly grooved and provided with similarly constructed grooves, in which the sliding blocks F, hereinbefore described, operate, and each of the side pieces is provided centrally with the connecting web or wall adjacent to the grooves A', through which shaft D passes, so that the 75 shaft of the rotary piston will have a solid bearing in these side pieces.

The rotary piston is provided on its periphery with a band or projecting flange, e' , which 80 will fit snugly against the said pieces and prevent the steam escaping from the steam-passage into and through the grooves.

To the exterior of the casing A is attached a covering-plate, C', which is provided with 85 extended portions, as shown, and also with perforations which correspond as to locality with the steam-entrance ports g and g' and exhaust-ports h and h' , and this plate is also provided with openings m and m' .

90 The plate C' is recessed on its inner side, so as to provide guide and passage ways for the reciprocating valves n and n' , and said plate is further grooved for the reception of bars o , which connect the valves to each other and to the 95 means for operating the same. The two valves n , which cover the upper entrance-ports, are connected to each other by a bar, p , which is reciprocated horizontally by a rock-bar, p' , and
